CASTING OF PRINTING FURNITURE

Basil Monrad Lansen, Sydney, New South Wales,
AustraliaApplication September 18, 1931, Serial No.
563,610, and in Australia April 1, 1931

2 Claims. (Cl. 199—55)

This invention has reference to the casting of slugs or strips constituting printing furniture, that is to say, strips of metal employed in the printing art, capable of being arranged side by side or in rectangular form to fill the spaces between lines of type assembled in a chase; and employed also in setting up in a chase, knives and rulers used in cutting and creasing cardboard to form cartons.

More particularly the invention has reference to slugs or strips having their ends stepped or otherwise shaped to allow of their being interlocked when disposed in rectangular form.

Printing furniture, of the kind referred to, at present in use is formed from a particular metal alloy by means of a special machine, and having been used is no longer of value to the printer for setting up purposes, except in subsequent cases requiring furniture of identical dimensions.

The object of my invention is to make provision for the casting of the required furniture from ordinary type metal on typographic composing machines, such as those marketed under the trade marks "Intertype" and "Linotype". Economy of metal is thereby effected and setting up of the type matter or cutting and creasing means is facilitated.

Machines of the type referred to incorporate a rotatable mould disc having a plurality of moulds disposed radially about its centre which are adapted to be moved into a position between a melting pot containing molten type metal, and means for supporting matrices conveyed from the magazine of the machine and justified by operation of the usual keyboard.

According to my invention in its application to a Linotype machine, I insert a cut-away liner or filling strip of suitable width, under the mould cap, at each end of one of the moulds formed in or on the rotatable mould disc. One of these cut-away liners or filling strips projects into the mould a distance equal to the width of the furniture to be produced, serving to form a step at one end of the furniture.

To allow of the molten metal, delivered from the melting pot entering that portion of the mould immediately above the projecting portion of said liner or filling strip, I partly cut away the ribs formed on the corresponding end of the mould cap.

I also provide an ejector blade of appropriate length for pushing the cast furniture from its mould into a chute below by means of which the furniture is delivered to the tray provided at the front of the machine for reception of slugs cast thereby.

Should it be desired to form a step at both ends of the furniture I may employ two extended liners or filling strips, one being inserted at each end of the mould, in which case the ribs at

both ends of the mould cap would be cut away as hereinbefore explained.

Where the furniture is required for the setting up of type matter or cutting and creasing means which will be subjected to much use, it is advisable to reduce the height of the furniture in order to allow of its tendency in common with other printing furniture, to creep towards the level of the type faces or edges of the cutting and creasing means as the case might be, and interfere with the efficient out-put of the machine in which the chase is mounted.

To provide for this the height of the furniture may be reduced by cutting in the usual manner, but preferably I employ a filling strip having its face formed complementary to the front portion of the moulding cavity, and capable of being held in one of the usual slide blocks, say a border block, employed in the machine, so that the breadth of said cavity will be reduced accordingly.

But in order that my invention may be clearly comprehended, and readily carried into practical effect, reference is now made to the drawings accompanying and forming part of this complete specification and which show part of an "Intertype" mould.

Figure 1 is a front elevation showing in broken lines a mould disc of the type employed in the beforementioned composing machines, and in full lines one of the moulds, embodying my improvements, mounted thereon.

Figure 2 is a perspective view on an enlarged scale of the mould cap seen in Figure 1, and the liners adapted to be interposed between said cap and the body of the mould.

Figure 3 is a perspective view of a piece of the furniture produced in accordance with my invention, of the maximum size capable of being cast when the mould cap shown by Figure 2 is employed.

Figure 4 is a plan view of a chase containing type matter set up with the aid of furniture produced in accordance with my invention.

Figure 5 is a similar view of a chase illustrating the utility of the furniture in the setting up of knives and rulers for cutting and creasing cardboard blanks in the production of cartons.

Figure 6 is a perspective view of portion of the filling strip used to produce furniture of less height than that illustrated by Figure 3.

Figure 7 is a perspective view of portion of a matrix slide block of the kind usually employed in conjunction with the mould disc shown in Figure 1, wherein the filling strip illustrated by Figure 6 is adapted to be held.

Figure 8 shows in plan view, for the purpose of comparison, the right hand end of the piece of furniture shown in Figure 3, and in juxtaposition with it the corresponding end of a piece of the

furniture produced when the filling strip shown by Figure 6 is employed.

The mould disc 9 shown in Figure 1 has the usual means provided on it for the mounting of a plurality of moulds about its centre.

One such mould is shown in the uppermost portion of this figure. Each comprises a body portion 10, cap 11 and liners 12 adapted to be interposed between said body portion and its cap. The moulding cavity is designated by the reference numeral 13.

The cap 11 is of usual construction, but in accordance with my invention has two of its ribs 14 partly cut away to allow the molten type metal sprayed into the cavity 13 as ordinarily, to extend into the portion of the cavity immediately above that portion of the left hand liner 12 which extends into the mould cavity.

The co-operation of liners 12 with the mould cap, to produce the furniture illustrated by Figure 3 will be clearly understood on reference to the first two figures of the drawings.

In Figure 2 the liners 12 are shown in full lines apart from the mould cap 11, the dotted lines indicating the position they would occupy relatively to the cap in the assembled mould.

The left hand liner 12 projects into the moulding cavity 13 a distance equivalent to the width of the furniture 15, in order that four pieces of the furniture may be interlocked to produce a rectangular space as illustrated in Figures 4 and 5.

The furniture 15 is actually a slug having a plain face 16, and one reduced end portion 17 formed with the aid of the left hand liner 12 and by the cutting away of the two left hand end ribs 14 of the cap.

Figure 4 serves to show the furniture 15 as used in the setting up of type matter 18, in a chase 19, together with ordinary wood, and metal, furniture 20 and 21 respectively, and the usual quoins 22.

In Figure 5 the assembled furniture 15 is surrounded by knives 23 and rulers 24, the whole being clamped in the chase 19 in the usual manner.

To produce the smaller furniture shown in Figure 8, the filling strip 25 illustrated by Figure 6 is employed.

This strip 25 has a plurality of recesses 26 formed on its face, complementary to the outer ends of the ribs 14 of the mould cap 11, in order that it may be capable of blocking the foremost portion of the mould cavity 13 throughout the whole of its length.

The strip 25 is shaped on its rear face for insertion in the slide block shown in Figure 7, whereby it may be directed into the mould cavity 13 on movement of the usual matrix elevator of the machine in well known manner.

The furniture is removed from the mould in the ordinary way by operation of the usual plate provided for ejecting slugs produced by the machine, but care must be taken to select a plate for this purpose that will pass between the liners 12.

It will be obvious that the cutting away of the ribs 14 of the cap 11 in the manner explained does not preclude the use of the cap in the production of the ordinary type face slugs. In the case of a "Linotype" mould the lines would also require to be cut away at the ends in addition to the ribs, as will be readily understood by those versed in the art.

I claim

1. Means for the casting of slugs for use as furniture, comprising a mould body, a mould cap therefor, said mould cap being provided with spaced ribs extending from the rear to the front of the mould cavity and certain of said ribs being cut away, and a liner disposed beneath the cut away portion of the mould cap for forming a step in the slug cast in said mould body.

2. Means for the casting of slugs for use as furniture, comprising a mould body, a mould cap therefor provided with spaced ribs extending from the rear to the front of the mould cavity, a filling strip for reducing the cavity having a plurality of recesses formed on its face complementary to the outer ends of the spaced ribs on the cap, said mould cap being cut away at certain of the ribs, and a liner disposed beneath the cut away portion of the mould cap for forming a step in a slug cast in the said mould body.

BASIL MONRAD LANSER.
